UNITED STATES PATENT OFFICE.

DAVID E. WANGER, OF WINNETKA, ILLINOIS.

EXERCISING DEVICE.

Application filed November 5, 1920. Serial No. 421,902.

To all whom it may concern:

Be it known that I, DAVID E. WANGER, a citizen of the United States of America, and a resident of Winnetka, county of Cook, State of Illinois, have invented certain new and useful Improvements in Exercising Devices, of which the following is a specification.

This invention relates to a simple appliance for use in physical culture exercises and designed to keep the muscles of the arm and body in a natural state of tension during such exercises, the purpose being to improve the circulation and bring more muscles into action than normally.

The objects of the invention are accomplished by the device shown in the accompanying drawings wherein—

Fig. 1 is a perspective view illustrating how the use of the device produces a natural spread and tension of the fingers which in turn results in effecting a tension of the arm and related muscles.

Fig. 2 is a side view of the device.

Fig. 3 is a sectional view thereof.

Fig. 4 is a sectional view taken on the line 4—4 of Fig. 2.

The device by which the invention is practiced comprises a ball suitably shaped and designed to be encircled and compressed by the fingers of the user against the desired resistance. Overcoming this resistance results in effecting the desired tension of the muscles and maintaining the fingers spread

properly as is also desired during the exercises.

The device consists of two hemispheres 1 and 2 secured together by a headed pin 3 seated in the conical recess 4 of the part 2. The head is movable in the cylindrical aperture 5 during compression and expansion of the ball. The resistance to compression is afforded by a plurality of springs 6 seated in the recesses 7.

I claim:

An exercising device comprising a pair of semi-spherical members arranged in the form of a ball adapted to be gripped in one hand, a central guide post along which one of said members is movable toward the other, the opposed flat faces of said members having a plurality of annularly arranged recesses formed therein at equal radial distances from said guide post, the recesses of one of said members being alined with those of the other member, and a plurality of compression springs arranged between said members and having their opposite ends seated in said alined recesses, said springs normally urging said members away from each other so as to spread the fingers of a hand encircling said ball by exerting pressure radially in substantially all directions.

Signed at Chicago this 3rd day of November, 1920.

DAVID E. WANGER.
